UNITED STATES PATENT OFFICE.

ESTEN ANDERSEN, OF CHICAGO, ILLINOIS.

RAFTER-FRAMING TOOL.

Application filed October 6, 1926. Serial No. 139,927.

This invention contemplates the provision of a two-way bevel square, which is particularly useful and advantageous for roof framing, although its general use and application is contemplated by the claim.

In carrying out the invention I contemplate a device of the above mentioned character, wherein the component parts can be quickly and conveniently arranged at any desired angle, and said parts folded to provide a comparatively small instrument when not in use.

The nature and advantages of the invention will be better understood when the following detail description is read in connection with the accompanying drawings, the invention residing in the construction, combination and arrangement of parts as claimed.

20 In the drawings forming part of this application like numerals of reference indicate similar parts in the several views and wherein:

Figure 1 is a side elevation of the device showing the manner of using the same.

Figure 2 is a view taken at a right angle to Figure 1.

Figure 3 is a view similar to Figure 2 showing how the device is folded.

30 Figure 4 is a view of the device folded taken at a right angle to Figure 3.

Figure 5 is a perspective view of one limb of the device.

Figure 6 is a similar view of the other limb.

35 Figure 7 is a sectional view on line 7—7 of Figure 4.

The device forming the subject matter of the present invention includes a pair of pivotally connected limbs clearly illustrated in

40 Figures 5 and 6, the limb shown in Figure 5 being made up of spaced sections 10 which are joined together at their lower ends, to provide a space therebetween for the reception

45 of the limb 11 shown in Figure 6. This limb is comparatively wide adjacent one end as at 12 and provided with a slot 13 adapted to fit between the sections 10 at the upper ends thereof, which are provided with open-

50 ings 14 registering with the slot 13 to receive the bolt 15 which has a thumb nut 16 associated therewith. By reason of this construction it is manifest that the limb 11 can be swung upon its pivot to any angular position with relation to the limb sections 10,

55 and may also be adjusted toward and away

from the limb sections as the occasion may require by means of the slot 13. The limb 11 is adapted to fold between the limb sections 10 when not in use as clearly shown in Figures 4 and 7, one edge of the limb being relatively thick to provide shoulders 17 adapted to engage the adjacent edges of the section 10 of the other limb, to limit the movement of the limb 11 when being folded. The forward edges of the sections 10 are provided with lateral flanges 18 as clearly shown in Figure 5, and these flanges adjacent the upper end of the limb are provided with slotted extensions 19 to accommodate the adjustable wings 20.

As shown in Figure 2 there is one of these wings for each slotted extension 19, each wing including a curved edge 21 and a straight edge 22, while projecting from the

55 curved edge at an appropriate point in the length of the wing is an apertured lug or ear 23. Each ear 23 supports a threaded bolt adapted to be received by the adjacent slotted extension 19 and which bolt has a thumb

60 nut 24 threaded thereon so that the wings can be held fixed relatively to the limb 10 in any given position. These wings are capable of

65 being wholly removed from the extensions 19 and their positions reversed from that shown in Figure 3 to that shown in Figure 2, when use of the wings is desired. It will be noted that in the normal position of the wings in

70 Figure 3, the straight edges 20 are arranged to contact the adjacent sides of the sections 10, with the pointed extremity of each wing

75 arranged behind the adjacent flange 18, thus protecting this end from being injured in any way while the device is in its folded condition. As above stated, when use of the

80 wings is desired, they are removed from the slotted extensions 19 and their positions reversed with relation to said extensions, so as to arrange the straight edges outermost.

As above stated, the limb 11 can be arranged at any designed angle to the limb sections 10 and is used for the plumb cut, while the wings 20 are susceptible of adjustment

85 with relation to the limb sections 10 and are used for the side or cheek cut. The tool of course can be used either right or left. When

90 setting the tool for use one of the wings 20 should be first arranged at the proper angle, after which the limb 11 is set for the plumb cut, and by shifting the limb 11 toward and

95 away from the limb sections 10 through the slot 13, the sharp corners or points of this

limb can be arranged to meet the pointed end of the adjacent wing. The other wing is then set accordingly and the entire tool is then ready for use. When the wings 20 are 5 folded against the sides of the limb sections 10, and the limb 11 folded between the said sections, the entire tool can be reduced to a small compact article which will occupy but a minimum of space in a tool kit 10 or the like.

While it is believed that from the foregoing description, the nature and advantages of the invention will be readily apparent, I desire to have it understood, that I 15 do not limit myself to what is herein shown and described and that such changes may be resorted to when desired as fall within the scope of what is claimed.

What is claimed is:

20 A bevel square of the character described comprising a limb including spaced sections, the upper ends of which are reversely offset, a second limb having an offset slotted exten-

sion, slidably and pivotally associated with the offsets of the first mentioned limb, said 25 second limb being capable of being arranged at any desired angle with relation to the first mentioned limb, or folded between the sections thereof, means for releasably holding said limbs fixed relatively, slotted extensions 30 projecting laterally from the first mentioned limb, wings slidably and pivotally mounted on said extensions and capable of being arranged at desired angles with relation to said limb, each wing including a curved edge and a straight edge terminating in a pointed extremity for said wing, said wings being each capable of being reversed on the extensions so as to present either edge to the adjacent side of the first mentioned limb, and to enable the 40 wing to be folded parallel with the latter when not in use, and means for holding said wings fixed relatively to said limb.

In testimony whereof I affix my signature.

ESTEN ANDERSEN.
